UNITED STATES PATENT OFFICE.

ALEC STUART DAVIDSON, OF LONDON, ENGLAND.

LOCOMOTIVE AND OTHER BOILER OR STEAM GENERATOR.

Application filed December 9, 1924, Serial No. 754,924, and in Great Britain March 10, 1924.

This invention relates to locomotive and other boilers or steam generators.

The invention has for its principal object to provide a simple and highly efficient steam superheater having a large or maximum heating surface and so arranged as to be readily accessible for examination or removal and renewal of its various parts. A further object of the invention is to provide a steam generator which shall be simple and compact in construction while at the same time providing a relatively large or maximum evaporating surface.

Although the present invention will be described hereinafter with reference to locomotive boilers and like steam generators, of the smoke or fire-tube type, it is to be understood that the invention is not restricted to such steam generators. When embodied in a locomotive steam generator of the smoke-tube type the present invention renders unnecessary the usual enlarged flues or smoke-tubes heretofore usually provided to accommodate the steam superheater, which enlarged flues are a source of trouble in locomotive boilers as well as entailing a reduction in smoke-tube heating surface. The present invention enables all the smoke tubes of the boiler to be of the usual small diameter, thus enabling the maximum smoke-tube heating surface to be obtained or maintained. Further such smoke-tubes are unobstructed by the insertion therein of superheating pipes or elements, thus providing for free passage of the gases of combustion through such smoke-tubes and easy cleaning of such tubes.

In a steam superheater according to the present invention the flow of steam through the superheater is decelerated as compared with the flow of steam in the well known types of smoke or fire-tube superheaters as heretofore fitted to locomotive and like smoke or fire-tube boilers; this deceleration is due to the considerably larger number of superheater elements that can be accommodated in a steam generator having a superheater constructed and arranged according to this invention. Further with the superheaters according to this invention a higher temperature of superheated steam can be obtained. Further with this invention the objectionable drop in steam pressure which occurs in the usual superheaters of the smoke or fire-tube type, due to wire drawing, is prevented. The drop in steam pressure as

between the boiler and the outlet for superheated steam from the header or headers is effectively prevented so that at the outlet for the superheated steam from the header or headers the steam pressure will approximate to the boiler steam pressure, and the pressure of steam at the engine valve chests will also approximate to the boiler steam pressure.

With the constructions and arrangements according to this invention the usual longitudinal stays extending through the steam space of a locomotive type boiler, from the front of the fire-box to the smoke-box or uptake end of the boiler, may be reduced in number, or eliminated, and be replaced by smoke-tubes, leading from the fire-box to the front or smoke-box end of the boiler, serving in a highly efficient manner as longitudinal stays.

Further, in a steam generator with superheater according to this invention a water tube fire-box construction or equipment may be employed and the evaporative efficiency of the boiler be thus considerably increased as compared with boilers of the locomotive or like smoke or fire tube type of the usual construction. Other advantages provided by this invention will be understood and appreciated, by those skilled in the art, from the description of embodiments thereof hereinafter given.

The invention principally consists of a locomotive or other boiler or steam generator of the type above specified in which a steam superheater or steam superheaters is or are provided within a superheating space or chamber, or spaces or chambers, within or enclosed by the casing or shell of the fire-box or furnace chamber, the said superheating space or spaces being shut off from communication with the steam and water spaces of the boiler and being in communication with the smoke box or uptake of the boiler through suitable tubes or ducts and also in communication with the fire-space or furnace chamber through suitable spaces, openings or ducts leading therefrom. The communication between the superheating space or spaces and the smoke-box or uptake is preferably effected by smoke or fire-tubes passing through the steam or water space, or both, of the body of the boiler, and the openings or ducts forming communication between the fire-box or furnace chamber and the said superheating spaces or

- chambers may be through the side wall or walls or crown of the furnace chamber for the passage of furnace gases or gases of combustion into said superheating space or spaces, and the said openings or ducts are preferably provided towards or adjacent the fire hole or fire door end of the furnace chamber or fire space and for a suitable distance towards the opposite end.
- 10 The invention further consists in a steam superheater arranged as above mentioned and comprising a header or headers for distributing saturated and collecting superheated steam and superheating pipes or elements arranged in such a position or positions in the above mentioned superheating space or chamber as to be heated by the gases of combustion from the furnace chamber in their passage through such space or chamber before such gases pass into and through the boiler body to the smoke box or uptake.
- 15 The invention further consists in the details of construction, arrangement and combination of parts pointed out in the appended claims and hereinafter particularly described with reference to the accompanying drawings, in which,—
- 20 Fig. 1 is a transverse sectional elevation of the fire-box of a locomotive boiler in which the side wall water spaces of the fire-box or furnace chamber are constituted by water tubes, the figure illustrating one embodiment of the invention and being a view looking towards the fire-box tube plate of the boiler.
- 25 Fig. 2 is a central longitudinal vertical section of the fire-box shown in Fig. 1.
- 30 Figs. 3 and 4 are views similar to Figs. 1 and 2 but illustrating another embodiment of the invention.
- 35 Fig. 5 is a sectional plan, the section being taken on the lines X—Y, Figs. 2 and 4, of one side wall of the fire-box or furnace chamber shown in those figures.
- 40 Fig. 6 is an elevation, to a larger scale, of certain parts shown in Figs. 3 and 4 and hereinafter described, and
- 45 Fig. 7 illustrates, to a larger scale, the arrangement of the upper portions of some of the upflow water tubes or the fire-box in order to provide for the passage of gases of combustion to the superheaters, as hereinafter described.
- 50 Referring to the drawings, in the embodiments of the invention therein shown, a steam superheater is provided in each of two chambers or spaces 1 within the upper portion of the fire-box shell or casing, one at each side thereof, each such space 1 being closed on its outer side by the plates 2 forming the fire-box shell or casing and on its inner side closed or separated from the fire-space or furnace chamber proper by a water-jacket wall consisting of or comprising a
- 55 number of vertically arranged water tubes 3 which are arranged in a row or rows along each side of the fire-space or furnace chamber, the lower ends of the said tubes being connected with leaders or chambers 4 at each side of the fire-box and situated adjacent to, preferably a little below, the fire grate or fire bars 5, the upper ends of the said tubes being connected to and communicating with a drum or chamber 6 in the upper portion of the fire-box and in free communication at 75 its ends with the usual water spaces 7, 8 of the boiler at the front and rear of the fire-box, these water tubes 3 being preferably so arranged as to form continuous or practically continuous walls or water-jackets at each 80 side of the fire-box or furnace chamber; spaces or openings 3^a, see Figs. 1 and 3, are provided in or through the upper portions of the said water-jacket or water tube walls 3 for a portion of their length (which may 85 be about one-half the length) from the fire-hole or fire-door end of the fire-box towards the opposite or front end of the fire-box.
- 89 Each of the spaces 1 is shut off from communication with the steam and water spaces 90 of the boiler and each said space is in communication, through smoke or fire tubes 9, with the smoke box at the front end of the boiler, the rear ends of said fire tubes being secured, preferably expanded, in holes in the 95 front wall or plates of the fire-box which constitutes the front end of the said chambers or spaces 1, and the front ends of the said fire tubes are similarly secured in the smoke box tube plate of the boiler. These 100 smoke or fire tubes, which extend through the water space of the boiler and some, it may be, through the steam space of the boiler, form longitudinal stays, and are preferably small or relatively small tubes for 105 instance of the same or approximately the same diameter or cross-area as the usual smoke or fire tube of a locomotive boiler.
- 110 The steam superheater in each of the spaces 1 consists of a number of pipes 10 each of which may be bent to form a U-loop element the ends (i. e. saturated steam inlet end and superheated steam outlet end) of each of said elements being secured, preferably expanded, as shown, in holes in a wall 11 of 115 a header 12 comprising a saturated steam chamber 13 and superheated steam chamber 14, the superheated steam chamber 14 being arranged in communication, through a conduit passing through the front wall or plates 120 at the front end of the fire-box and through a pipe 15, which the cylinder valve chests of the engine. The saturated steam chamber or header 13 receives saturated steam through a pipe 16 leading from the regulator valve 125 either externally of the boiler, as shown in Figs. 1 and 2, or through the steam space in the boiler barrel as shown in Figs. 3 and 4.
- 130 In the embodiment of the invention shown in Figs. 1 and 2 the header 12 in each of the

spaces 1 may be and is shown as a casting comprising two longitudinal steam chambers 13 and 14 separated by an internal wall or partition, and each said header extends longitudinally of the fire-box casing for the full or nearly the full length thereof so that a large number of superheater elements 10 may have their inlet and outlet ends connected respectively with the saturated and superheated steam chambers 13, 14 in the said headers. The top or outer side of each header opposite to the wall 11 in which the ends of the superheater elements are secured is provided with a removable cover plate 17 (or it may be cover plates) secured by studs and nuts to the header and closing openings in said outer side or top through which tools may be inserted for expanding or securing the ends of the elements in the wall 11 and for disconnecting or driving out these ends when necessary. Tubular extensions 15^a, 16^a are provided on the front end of the header with flanges to which the pipes 15 and 16 are respectively connected.

25 The draught through the smoke tubes 9, through which gases of combustion pass from the fire-box via the chambers 1 to the smoke-box, may be controlled by means of a damper or dampers (not shown) in the smoke box at the forward ends of said fire tubes. Such damper or dampers may be operated and controlled mechanically by connections operable from the foot plate of the locomotive, or the said damper or dampers may be operated and controlled by a steam operated dash-pot or cylinder controlled by a valve at the foot plate.

Where the water-jacket walls of the fire-box or furnace chamber consist of water tubes there may be an inner and an outer row of vertically disposed water tubes along each side of the fire-box as shown and the tubes 3 of the inner row may be of small or relatively small diameter or cross-area while the tubes 18 of the outer row may each be of relatively large diameter or cross-area; in the construction shown the upper ends of the tubes 3 are arranged in communication with the steam and water drum 6 in the upper portion of the space enclosed by the plates forming the shell or casing of the fire-box. As shown the lower portion of the drum 6 forms a portion of the top or crown of the fire space or furnace chamber.

55 The large diameter water tubes 18 are connected to and communicate at their lower ends with the water chambers, headers or junction boxes 4, the upper ends of these large tubes 18 being connected to and communicating with upper water chambers, distributors or ducts 19 extending along each side of the fire-box within the space enclosed by the shell plates forming the outer casing or wall of the fire-box. In the construction shown the water distributors 19 are situated

with their central horizontal planes on or approximately on the central horizontal plane of the fire-box tube plate 20, and the said water distributors 19 extend longitudinally from end to end of the fire-box and are indirect and free communication at their opposite ends, through apertures in the front and rear walls or plates of the fire-box or furnace chamber, respectively with the water space within the boiler barrel 7 and the water space 8 at the fire-door end of the fire-box.

The water tubes 18 receive relatively cool water through the distributors 19 and convey the water to the junction boxes 4 whence the water passes up through the tubes 3 into the steam and water drum 6.

For the purpose of enabling the gases of combustion to pass from the fire-box or furnace chamber into the chambers 1 the upper end portions of the small water tubes 3 are so bent or arranged that these portions of adjacent tubes are in staggered relation to one another thus providing spaces or openings 3^a, Fig. 7, between the said portions of the tubes through which spaces 3^a the gases of combustion can pass from the furnace chamber into the spaces 1 containing the superheaters, the gases in their passage through the spaces 1 sweeping on and about the superheater elements or pipes 10. The staggered arrangement of the upper portions of the small water tubes 3 at each side of the fire-box is provided only for a predetermined distance, along the row of tubes, from the fire-hole end of the fire-box towards the opposite end of the fire-box, for instance for about half the distance from the fire-hole end to the forward or boiler body end, the corresponding upper portions of the remainder of the tubes 3 being arranged or maintained side by side in close proximity or in contact with each other so that the forward portion of the row of tubes 3 constitutes a solid or substantially solid or closed wall for the furnace chamber and for the inner side of the space 1 in which the steam superheater is located. These arrangements enable the smoke box draught to be effective for withdrawing a suitable portion or quantity of the gases of combustion from the furnace chamber into the superheater chamber, the remaining gases of combustion passing direct from the furnace through the usual smoke or fire tubes within the boiler barrel or body.

The staggered arrangement of the upper portions of the water tubes 3 may be such that the openings or spaces 3^a between these portions of the tubes, for the passage of the gases of combustion into the chambers containing the superheaters, may extend upwardly from about the level of the water distributors 19 to the steam and water drum 6.

Each of the water tubes 18 of large or relatively large cross-area is preferably made of a more or less flattened form in cross-section between its upper and lower ends, the said ends being circular in cross-section. The flattened water tubes 18 are arranged side by side and close together in the row (except at their short circular ends) so as to form a continuous or practically continuous outer wall for the fire-space or furnace chamber. The water tubes 18 also lie close to or abut against the water tubes 3 at the side thereof remote from the furnace.

As will be seen on reference to Fig. 1, each of the elements 10 is bent at three places to form U-shaped loops 10^a, 10^b being the return bends, and each element is so arranged that its return bend 10^a is situated towards and adjacent the drum 6, the other return bends 10^b of the element being situated towards and adjacent the inside of the plates 2 forming the casing or shell of the fire-box. The saturated steam inlet and superheated steam outlet end portions of each of the elements are bent upwardly or outwardly towards the bottom or side 11 of the header 12 to which they are connected.

The headers 12 are situated adjacent the inside of the top plate of the fire-box casing, one on each side of the drum 6, and each header with its bottom or side 11 at an angle to the central vertical plane of the fire-box corresponding to that at which the loops or U-shaped portions of the superheater elements lie. On opposite sides of the header 12 laterally projecting lugs, plates or flanges 11^a, 11^b are provided whereby the header may be secured to the inside of the plate or plates forming the casing or shell of the fire-box and to the drum 6 to the sides of which drum suitable brackets may be secured for supporting the header at that side.

Each of the water distributors 19 forms the bottom or closure for the lower side of the respective space 1 in which a steam superheater is located; in the construction shown the opposite or inner and outer sides of the distributors 19 lie close to or abut against the outer sides of the water tubes 3 and the inside of the plates forming the casing or shell of the fire-box.

In the alternative and preferred embodiment of the invention shown in Figs. 3, 4, 5 and 6, the superheater in each of the spaces 1 in the upper part of the fire-box comprises a small or comparatively small header 12, which, as in Figs. 1 and 2, may be a casting and which has two steam chambers 13, 14 separated from each other by an internal partition or wall extending longitudinally of the header; this header is arranged relatively close to the front plate of the fire-box and with its internal parti-

tion wall lying at an angle to the central vertical plane of the fire-box. In this embodiment of the invention each superheater element 10 consists of a simple U-shaped pipe extending longitudinally of the space 1, preferably nearly to the rear water space 8, the forward ends of each said element being secured in the wall 11 of the header 12 so as to respectively communicate with the saturated steam chamber 13 and with the superheated steam chamber 14 therein, these ends of the elements being preferably expanded in holes in the wall 11 of the header. Openings are provided in the opposite side of the header (facing the water space 7 of the boiler) through which a tube expander may be inserted for expanding the ends of the elements in the holes in the rear wall 11, these openings being closed by a cover plate or cover plates 17 secured by studs and nuts. On the cover plate 17, or on one of the cover plates, if a plurality be employed, there is provided a tubular extension 16^a, which may be formed integrally with the cover plate, having at its forward end a flange, which may have an annular spigot or projection for connection to the end of the saturated steam pipe 16 leading from the regulator to the saturated steam chamber in the header. A tubular extension is provided on, or a pipe 15^a is secured to, the outer or upper side wall 14^a of the header and in communication with the superheated steam chamber therein; the forward end of this pipe 15^a is secured, for instance by a flange and studs and nuts, in registration with a hole through the front plate of the fire-box adjacent to the top of the fire-box casing, the superheated steam pipe 15 to the engine valve chest being connected with this pipe or tubular extension 15^a. This superheated steam pipe 15 may be arranged to extend exteriorly of the boiler barrel as indicated in the drawings, or it might be arranged to extend through the steam space in the upper part of the boiler barrel and through the smoke box tube plate.

Each superheater element 10 comprises two straight portions or legs connected by a return bend portion 10^a at the end of the element adjacent the back water space 8 and the greater number of such return bends are bent or kinked, as at 10^c, Fig. 6, in a lateral direction relatively to the transverse plane of the header on which the ends of the element connected thereto lie, so that the centre of each such return bend portion lies to one side of the longitudinal pipe forming a leg of an adjacent element, whereby any individual one of the elements so formed can, if necessary, be disconnected and removed from the header without disturbing any of the other of such elements; an end view of such an element, looking forwardly or to-

wards the header, is thus more or less of a flattened V-shape as seen in Fig. 6. Alternate elements of the group of elements so formed are preferably somewhat shorter than the other elements of the group.

The holes in the rear wall 11 of the header to which the inlet and outlet ends of the superheater elements are secured are preferably arranged in rows transversely of the header as shown in Fig. 6, in which arrangement, starting at one end of the header, there is a transverse row of four holes, two of which open into the saturated steam chamber and two into the superheated steam chamber and which accommodate the inlet and outlet ends of two superheater elements, while in the next adjacent row there are two holes, one leading into each chamber of the header and accommodating the inlet and outlet ends of one superheater element; in the next row there are again four holes, and so on in alternate rows. The arrangement of these holes, as regards each compartment of the header, is also such that they are also in rows longitudinally of the header, the holes in adjacent longitudinal rows, as well as those in adjacent transverse rows, being arranged in staggered relation. In the construction shown, — see Fig. 6, — there are six longitudinal rows of holes in the wall 11, the holes of three rows being in communication with the saturated steam chamber 13 of the header and the holes of the other three rows in communication with the superheated steam chamber 14 of the header. The longitudinal pipes of the elements whose outlet ends are secured in the holes in the outermost longitudinal row adjacent to the outer side wall 14^a and the longitudinal pipes of the elements whose outlet ends are secured in the next or adjacent longitudinal row of holes are arranged to lie closely side by side in a row forming a continuous or practically continuous tubular wall as indicated in Fig. 6, the pipes of the elements whose ends are secured in the said next longitudinal row of holes in the header being set or bent outwardly at a short distance from their connection with the header wall, as at 10^a, Figs. 4 and 6, so that they occupy the spaces between the longitudinal pipes of the elements whose ends are secured in the holes in the outermost longitudinal row. In this way a protecting wall is formed which shields the plates of the fire-box casing above the superheater from the action of the hot gases of combustion and also shields the upper side of the superheater header and the superheated steam outlet pipe in connection therewith. The superheater elements which have the bent portions 10^a are shorter than the remaining elements as seen in Fig. 4, and, as will be seen in Fig. 6, their return bends 10^a are not

kinked or V-shaped as are those of the longer elements.

The header may be secured in place in any convenient manner. For instance at the outer end and at or adjacent to the lower side of the header there may be formed a projection (not shown) constituting a bracket or foot which may be adapted to rest upon and be secured to the water distributor 19. At the other end of the header another projection 12^a, Fig. 3, constituting a bracket may be provided or formed, this bracket being adapted to bear against and be secured to the adjacent side or wall of the drum 6.

The form or construction of the plates at the front or boiler end of the fire-box and their connection one to the other are such that the space between these plates below the boiler barrel is shut off from and thus does not communicate with the water space 85 in the boiler barrel, the said space being preferably filled with fire bricks as shown at 26, Figs. 2 and 4. The construction of the inner plates at front and rear of the fire-box is also such that the flanges for connection of these plates to the wrapper plates or casing of the fire-box and to the outer plates at front and rear of the fire-box do not project into the fire space or furnace chamber proper and are thus not exposed to the action of the flames and hot gases of combustion; the outer or front plate 21 and the inner plate 22 at the forward or boiler end of the fire-box have forwardly projecting flanges 21^a, 22^a formed on them for attachment to the wrapper plate or casing of the fire-box, and the outer plate has also formed on it a circular forwardly projecting flange 21^b to which the boiler barrel is attached. On the inner plate 22 three circular inwardly projecting flanges are formed which project into the upper portion of the fire-box casing above the fire-space or furnace chamber proper, one of said flanges 22^c being a relatively large flange to which the forward end of the drum 6 is secured, and the other two 22^d relatively small flanges adjacent to the opposite edges or sides of the plate and to which flanges the forward ends of the water distributors 19 are secured. The said inner and outer plates 22, 21 are connected (for instance riveted together) at their lower edges by means of a forwardly projecting flange 22^e, at the lower edge of the inner plate, having a downwardly projecting portion which lies against the outer plate 21 and which is secured (for instance riveted) thereto. The inner and outer plates 23, 24 at the rear or fire-hole end of the fire-box are provided with more or less similar flanges to those on the plates at the front end, both of these plates 23, 24 being flanged rearwardly for attachment of the wrapper

plate or casing 2 of the fire-box. A large circular forwardly projecting flange 23^c on the inner plate 23 serves for attachment of the rear end of the drum 6, and two smaller 5 forwardly projecting circular flanges 23^d adjacent the opposite sides or edges of the said plate 23 serve for attachment of the rear ends of the water distributors 19. The inner plate 23 is flanged rearwardly at 23^e 10 at its lower edge for attachment to the outer plate 24 against which the said flanged part 23^e abuts, and both these plates are suitably punched or cut and flanged to form the fire-hole 25.

15 Referring more particularly to Figs. 2, 4 and 5 there is preferably provided at each end of the inner row of small or relatively small water tubes 3, at each side of the fire space or furnace chamber, a large or relatively 20 large water tube 18^a of flattened form in cross-section, the lower ends of these tubes 18^a being connected to the junction boxes 4 and their upper ends to the large drum 6 in the upper part of the fire-box. 25 These tubes 18^a are therefore uptake water tubes, and serve not only to provide additional heating surface but also to insulate or protect the outer wall or casing of the fire-box from the flame and hot gases of 30 combustion, and tend also to prevent direct access of the flame to the spaces 1 in which the superheaters are located.

As hereinbefore described each superheater has its own independent superheated steam 35 delivery pipe 15 leading to the valve chests of the engine cylinders, the superheaters being themselves independent of each other. Provision might be made whereby, should it be necessary to put the superheater at one 40 side out of use (for instance for repairs) the superheater at the other side of the fire-box can supply superheated steam to both or all the valve chests of the cylinders.

If desired the lower portions of the relatively 45 small uptake water tubes 3 forming the inner rows of tubes along the sides of the furnace chamber may have their walls thickened, for instance in the process of drawing the tubes, such thickening being for the purpose of minimizing the effects of, or 50 compensating for, wear or abrasion of the said portions of the tubes through the erosive or abrasive action of solid fuel fed into the furnace chamber.

55 What I claim is:—

1. In a steam generator, a fire-box casing, fire-box end plates secured in the fire-box casing and forming with it parts of a space which is a portion of the steam and water space of the generator, a receiving drum secured to the fire-box end plates and communicating with the said space, a header arranged longitudinally at the lower part of the fire-box casing, a series of inner water 60 tubes connecting the said header with the

said receiving drum and forming with the latter one side of the fire-box and a portion of its top, gas passages being formed between certain of the said inner tubes, a water distributor arranged between the said inner tubes and the fire-box casing and communicating with the said space independently of the receiving drum, a superheater chamber being formed between the fire-box casing and the inner tubes and between the water distributor and the receiving drum and between the fire-box end plates, and a steam superheater arranged in the said chamber and communicating with the steam and water space of the generator. 70

2. A steam generator as set forth in claim 1, and having two similar sets of devices as set forth, arranged one set at each side of the receiving drum and forming two similar superheater chambers, and a superheater arranged in each superheater chamber. 80

3. A steam generator as set forth in claim 1, the said gas passages between the inner tubes being formed between the inner tubes at the rear portion of the fire-box side, so that the gases of combustion are admitted 90 to the said superheater chamber at its rear end.

4. A steam generator as set forth in claim 1, the said superheater comprising a header arranged in the front end portion of the superheater chamber, and U-shaped superheater pipes secured to the header and arranged longitudinally in the said chamber. 95

5. A steam generator as set forth in claim 1, the said superheater comprising a header arranged in the front end portion of the superheater chamber, and U-shaped superheater pipes secured to the header and arranged longitudinally in the said chamber, certain parts of the said superheater pipes being arranged in close proximity to each other to form a shield which protects the fire-box casing from the gases of combustion admitted to the said chamber. 100

6. A steam superheater as set forth in claim 1, the said superheater comprising a header arranged in the front end portion of the superheater chamber, and U-shaped superheater pipes secured to the header and arranged longitudinally in the said chamber, the return bends of the superheater pipes being kinked in a lateral direction relative to the transverse plane of the header. 115

7. A steam generator as set forth in claim 1, and provided also with outlet pipes for the gases of combustion having their rear ends communicating with the front end of the said superheater chamber and extending 125 forwardly through the said steam and water space of the generator.

In testimony whereof I affix my signature.

ALEC S. DAVIDSON.
